TEETER-TOTTER
Marvin S. Gowing, Kansas City, Mo.
Application March 3, 1954, Serial No. 413,844
3 Claims. (Cl. 272—30)

This invention relates to new and useful improvements and structural refinements in teeter-totters or similar amusement devices which are also commonly known as see-saws, and the principal object of the invention is to provide a device of this type which is simple in construction, durable in use and which readily lends itself to convenient and economical manufacture.

More specifically, the invention concerns itself with that type of a teeter-totter wherein the customary beam or board is rockable as well as rotatable about its supporting member, whereby the device combines the functions of a teeter-totter with those of a merry-go-round.

As is well known, devices of this nature usually embody in their construction some form of a support member, commonly an upright post having its lower end portion embedded in the ground, a mounting head which is rockably and rotatably positioned at the upper end of such a post, and a beam or board carried by and rockable as well as rotatable with the mounting head.

An important feature of this invention resides in the provision of what may be called a ball and socket connection between the mounting head and its supporting post, whereby the desired movements of the beam are efficiently facilitated. However, inasmuch as a ball and socket connection of this nature would also permit lateral tipping or rocking of the beam, that is, tipping or rocking in a plane transverse to its longitudinal axis, another feature of the invention resides in the provision of means for permitting rocking of the beam in the plane of its longitudinal axis only.

As is also known, it is a common expedient in devices of this type to adjust the beam longitudinally with respect to its mounting head, whereby the balance of the beam may be varied in accordance with the weight of different persons such as may occupy the seats with which the ends of the beam are usually equipped. In this respect, another feature of the invention resides in the provision of novel means for engaging and frictionally clamping the beam in a pre-adjusted position in the mounting head, the arrangement being such that the beam may be quickly and easily shifted when so desired, to effect the required amount of balance or unbalance, as the case may be.

Inasmuch as the required adjustability of the beam with respect to the mounting head eliminates the possibility of rigid securing means between the two, a further feature of the invention resides in the arrangement of the beam clamping means so that the beam cannot be separated from the head by unauthorized persons.

A still further feature of the invention resides in the structure of the mounting head per se, the same being formed from two similar and complementary half-sections which are separably connected together so as to facilitate convenient and expeditious installation or removal thereof on or from the ball of the supporting post member.

With the above more important objects and features in view and such other objects and features as may become apparent as this specification proceeds, the invention resides in the details of construction and arrangement of

2

parts as shown in the accompanying drawings wherein like numerals are employed to designate like components and wherein

Figure 1 is a side elevational view of the invention;
5 Figure 2 is a vertical sectional view on an enlarged scale, taken substantially in the plane of the line 2—2 in Figure 1;
Figure 3 is a fragmentary perspective view of the support member, mounting head, clamping plate and beam, 10 the clamping plate being shown without its fastening means and in a fully open position while the beam is shown by dotted lines;

Figure 4 is a fragmentary elevational view of the mounting head with the clamping plate closed and the beam shown in section; and

Figure 5 is a perspective view illustrating one of the half-sections of the mounting head, together with its associated guide.

With reference now to the accompanying drawings in detail, the teeter-totter is designated generally by the numeral 10 and embodies in its construction an upright support member such as a post 12 which has its lower end portion embedded in a suitable foundation 14 in the ground, while the upper end of the post is provided with a ball 16.

A mounting head 18 is formed with a socket 20 having the ball 16 disposed therein, so that the mounting head may rock as well as rotate with respect to the post 12. To facilitate assembly, the head 18 is composed of two similar, complementary half-sections 18a and 18b having abutting faces 18c disposed in a plane which bisects the socket 20. The two half-sections of the head are held assembled by means of a plurality of dowel pins 22 pressed in registering bores 24 with which the half-sections are equipped.

The upper portion of the head 18 is provided with an open-ended channel or recess 26 which has slidably positioned therein an intermediate portion of a beam or board 28. The ends of this beam or board are provided with 30 suitable seats 30, including handle bars 30a.

The beam 28, of course, is rotatable as well as rockable with the mounting head 18 on the ball 16 of the post 12. The ball and socket connection which is provided would ordinarily permit the beam to rock in all directions, but the invention provides means for permitting the beam to rock in one direction only, that is, in the plane of its longitudinal axis. These means consist of a pair of transversely spaced guides 32 which are disposed at the underside of the head 18 and are engageable with 45 opposite sides of the post 12, whereby the beam is prevented from lateral rocking or tipping. Each of the guides 32 is formed integrally with one of the two half-sections of the head and underlies the other half-section without being secured to the latter, whereby the two half-sections may be separated when so desired.

50 It will be apparent from the foregoing that by virtue of the slidable positioning of the beam 28 in the channel 26, the beam may be adjusted longitudinally with respect to the head 18, so that the balance of the beam may be varied in accordance with the weight of different persons occupying the seats 30. However, means are provided for frictionally clamping the beam in a pre-adjusted position in the head, these means consisting of a clamping plate 34 which is connected by hinges 36 to the head 18 at one side of the channel 26, while a fastener device 38 connects the plate 34 to the head at the other side of the channel. The plate is provided at the underside thereof with a resilient pad 40 to frictionally engage the beam when the fastener 38 is in its closed position as shown in 55 Figures 2 and 4.

The fastener device 38 is of an expandable type and 60 consists of a pair of brackets 42, 44 secured to the plate

34 and the head 18 respectively. A toggle link 46 is pivoted at 48 to the bracket 42 and is also pivoted at 50 to a second toggle link 52 which, in turn, is pivoted to the bracket 44 at 54. The link 46 is provided with a finger-piece 56 and when the fastener is closed, the toggle links 46, 52 are so disposed that the plate 34 is securely held in its clamping position. However, by simply grasping the finger-piece 56 and pulling the toggle link 46 outwardly as shown by the dotted lines 36a in Figure 4, the clamping plate 34 will be swung upwardly on its hinges 36 to facilitate adjustment of the beam 28 in the channel 26 of the head 18.

It is to be particularly noted that the length of the toggle links 46, 52 is such that the clamping plate 34 cannot be fully opened, in other words, the toggle links at all times connect the free end of the plate to the head 18. This arrangement is coordinated with the seats 30 and handle bars 30a at the ends of the beam 28, which seats and handle bars are of such size that they cannot pass through the channel 26 even when the clamping plate 34 is released. In this manner, the beam will be prevented from being separated from the mounting head by unauthorized persons.

Finally, it will be observed that one of the half-sections of the head 18 is provided with a bore 58 which extends outwardly from the socket 20 and is fitted in its outer end with a nipple 60, whereby lubricant may be injected into the socket to assure free movement of the head on the ball 16.

Although in the foregoing there has been shown and described the preferred embodiment of the invention, various modifications may become apparent to those skilled in the art to which the invention relates. Accordingly, it is not desired to limit the spirit and scope of the invention, but various modifications may be resorted to, such as may lie within the scope of the appended claims.

What is claimed as new is:

1. In a teeter-totter, the combination of a ball-shaped support member, a box-like head rotatably and rockably positioned on said support member, said head being provided with a channel-shaped recess having an open top and open ends, a beam extending through and adjustable longitudinally in said recess, said beam having a flat upper surface substantially coplanar with the upper surface of said head, a clamping plate hinged at one side thereof to said head at one side of said recess and ex-

tending transversely across the open top of the latter, and means provided at the relatively opposite side of said plate for releasably fastening the same to the head, said plate having a flat undersurface in frictional engagement with the upper surface of said beam, whereby to prevent the beam from shifting longitudinally in said recess when the plate is held in its clamping position by the fastening means.

2. The structure as set forth in claim 1 wherein said means for releasably fastening said plate to said head comprises a quick-acting clamp including upper and lower brackets secured to said plate and to said head respectively, a pair of toggle links pivoted to the respective brackets and pivotally connected together, said toggle

links being swingable from a locked position adjacent said head laterally outwardly to an unlocked position wherein said plate is simultaneously raised out of frictional engagement with said beam, and a finger-piece provided on one of said links.

3. In a teeter-totter, the combination of a support member including an upright post and a substantially spherical ball thereon, a box-like mounting head rotatably and rockably positioned on said support member and formed in its lower portion with a substantially

spherical socket rotatably receiving said ball therein, said head comprising a pair of complementary sections separably secured together and having abutting surfaces disposed in a plane which bisects said socket transversely of said head, and a pair of transversely spaced guides formed integrally at the underside of the respective sections of the head, the guide of each head section being elongated and extending complementally under the other head section and said guides being disposed at opposite sides of said post and being engageable with the latter,

whereby to prevent said head from rocking on said ball about an axis substantially parallel to said beam.
